UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

SECTION SWITCH.

Application filed October 9, 1920. Serial No. 415,789.

To all whom it may concern:

Be it known that I, WILLIAM SCHAAKE, a citizen of the United States, and a resident of Pittsburgh, in the county of Allegheny and State of Pennsylvania, have invented 5 a new and useful Improvement in Section Switches, of which the following is a specification.

My invention relates to section switches 10 for electric trolley systems, and especially to switches for isolating branch lines from the main trolley line.

The object of my invention is to simplify and improve the existing forms of section 15 break insulators such as are used, for instance, to break the connection between a branch line in the heading of a mine and the main trolley line, where the trolley conductor is located near the roof. It is quite important to have the branch line effectively insulated from the main line, while at the same 20 time means must be provided for readily connecting the lines.

Heretofore the difficulty has been to obtain, in a single structure, the necessary air 25 gap and also an effective switch mechanism. I provide a structure which combines these two features, and have illustrated one form thereof in the accompanying drawing, 30 wherein—

Figure 1 is a plan view of a section switch embodying my invention and

Fig. 2 is a side elevation thereof.

A pair of end members or blocks 3, of 35 conducting material having set screws 4, are provided to receive the ends of the trolley wires and maintain them in position. A third member 5 of similar material is located between the end members 3 and in spaced 40 relation thereto, the spaces forming air gaps to prevent the passage of current along the several members. The spaces, however, are narrow enough to permit the trolley wheel to travel along the under sides of the members 45 without the supply of current to the wheel being interrupted.

The three members, or blocks, are connected along their sides by a pair of wooden blocks 6, and castings 3 support a pair of 50 contact jaws 7, while the member 5 has a switch lever 8 pivoted thereon. A stop member 9 is provided to limit the movement of the lever 8 to the left.

A pair of hangers 10 are provided to support the switch from the roof of a mine,

and, as shown in Fig. 1, are located so as not to interfere with the movement of the switch blades 11.

When the lever 8 is moved to the left it carries the blades, simultaneously, out of 60 engagement with the stationary contact jaws and breaks the connection between the ends of the trolley wires.

By locating the pivot point of the switch midway between the stationary contact members, in the manner shown, a firm support for the blades is secured, and they are kept in alignment with the contact jaws. In those constructions wherein the blade is pivoted at one end, instead of midway of 70 its length, the free end of the blade may sway, or bend, to such an extent that it will not engage the stationary contact jaws in closing—especially where it is of sufficient length to bridge more than one air gap. 75

My invention is not limited to the specific structure illustrated, but may be modified in various ways, without departing from the scope thereof as defined in the claims.

I claim as my invention:

1. In a trolley-conductor section switch, the combination with metal terminal members connected to the ends of adjacent trolley-conductor sections and each having an intermediate metal member having a trolley-runner portion, a trolley-runner portion disposed in spaced alignment with said first trolley-runner portions to provide series-related air gaps in the conductor circuit, and a pair of flat insulating members extending 90 along the respective sides of the switch and transversely secured to all of said members, of a single switch for shunting the air gaps comprising oppositely facing stationary contact-jaw members disposed one on the upper 95 side of each terminal member, a horizontally disposed switch-lever plate vertically pivoted to the upper side of said intermediate member, and a pair of switch-blade members secured in position on the plate in flat surface 100 engagement therewith and projecting oppositely for co-operation with said stationary contact jaw members.

2. In a trolley-conductor section switch, the combination with metal terminal members connected to the ends of adjacent trolley-conductor sections and each having a trolley-runner portion, an intermediate 105 metal member having a trolley-runner portion disposed in spaced alignment with said

- first trolley-runner portions to provide series-related air gaps in the conductor circuit and insulating side members for supporting all of said members, of a single 5 switch for shunting the air gaps comprising a stationary contact member disposed on the upper side of each terminal member, a vertically-pivoted switch-arm structure movable in a horizontal plane above the device 10 for electrically connecting said intermediate member to each of said terminal members, and means on one of said insulating side members for limiting the opening movement of the switch.
- 15 3. In a trolley-conductor section switch, the combination with metal terminal members connected to the ends of adjacent trolley-conductor sections and each having a trolley-runner portion, an intermediate metal member having a trolley-runner portion disposed in spaced alignment with said first trolley-runner portions to provide series-related air gaps in the conductor circuit and insulating side members for supporting all of said members, of a single switch for shunting the 20 air gaps comprising a stationary contact member disposed on the upper side of each

terminal member, a vertically-pivoted switch-arm structure movable in a horizontal plane above the device for electrically 30 connecting said intermediate member to each of said terminal members, and a metal stop member secured to one of said insulating side members and projecting above the same into the plane of movement of the 35 switch-arm structure.

4. A trolley-conductor section switch comprising a plurality of spaced metal members each having a trolley-runner portion, insulating side members for supporting all of said metal members, oppositely-facing stationary contact jaw members disposed one on the upper side of each outer metal member, a switch blade device vertically pivoted to the upper side of an intermediate metal member to engage the open sides of said stationary jaw members, and a plurality of hanger-supporting means located adjacent the closed sides only of said 40 45 50 jaw members.

In testimony whereof, I have hereunto subscribed my name this first day of October, 1920.

WILLIAM SCHAAKE.

Certificate of Correction.

It is hereby certified that in Letters Patent No. 1,449,915, granted March 27, 1923, upon the application of William Schaake, of Pittsburgh, Pennsylvania, for an improvement in "Section Switches," an error appears in the printed specification requiring correction as follows: Page 1, lines 84 and 85, claim 1, strike out the words "an intermediate metal member having" and insert the same to follow after the word "portion", line 87; and that the said Letters Patent should be read with this correction therein that the same may conform to the record of the case in the Patent Office.

Signed and sealed this 8th day of May, A. D., 1923.

[SEAL.]

KARL FENNING,
Acting Commissioner of Patents.
